US00D697123S

(12) **United States Design Patent**
Takahashi et al.

(10) **Patent No.:** US D697,123 S
(45) **Date of Patent:** ** Jan. 7, 2014

(54) **SURVEILLANCE CAMERA**

(75) Inventors: **Masami Takahashi**, Kanagawa (JP);
Shinichi Murata, Osaka (JP)

(73) Assignee: **Panasonic Corporation**, Osaka (JP)

(**) Term: **14 Years**

(21) Appl. No.: **29/401,016**

(22) Filed: **Sep. 6, 2011**

(51) LOC (10) Cl. **16-05**

(52) U.S. Cl.

(57) **CLAIM**

We claim the ornamental design for a surveillance camera, as shown and described.

DESCRIPTION

FIG. 1 is a top perspective view of a surveillance camera of the present invention;

FIG. 2 is a front view thereof;

FIG. 3 is a rear view thereof;

FIG. 4 is a top view thereof;

FIG. 5 is a bottom view thereof;

FIG. 6 is a first side view thereof; and,

FIG. 7 is a second side view thereof.

The broken lines shown represent unclaimed subject matter and form no part of the claimed design.

1 Claim, 6 Drawing Sheets
